UNITED STATES PATENT OFFICE

152,085

DESIGN FOR A NECKLACE

William W. Hobé, New York, N. Y.

Application September 23, 1948, Serial No. 148,728

Term of patent 3½ years

(Cl. D45—16)

To all whom it may concern:

Be it known that I, William W. Hobé, a citizen of the United States of America, residing in New York city, county of New York, and State of New York, have invented a new, original, and ornamental Design for a Necklace, of which the following is a specification, reference being had to the accompanying drawing, forming part thereof, wherein:

The units of the necklace shown in dotted lines are identical in appearance to their corresponding units shown in solid lines.

I claim:

The ornamental design for a necklace, substantially as shown and described.

WILLIAM W. HOBÉ.
